CLAIM

The ornamental design for a luminaire as shown and described.

DESCRIPTION

FIG. 1 is a first perspective view of a luminaire according to a new design.

FIG. 2 is a second perspective view of the luminaire of FIG. 1.

FIG. 3 is a first end view of the luminaire of FIG. 1.

FIG. 4 is a second end view of the luminaire of FIG. 1.

FIG. 5 is a first side elevation view of the luminaire of FIG. 1.

FIG. 6 is a second side elevation view of the luminaire of FIG. 1.

FIG. 7 is a top plan view of the luminaire of FIG. 1.

FIG. 8 is a bottom plan view of the luminaire of FIG. 1.

FIG. 9 is a first perspective view of a luminaire according to a new design.

FIG. 10 is a second perspective view of the luminaire of FIG. 9.

FIG. 11 is a first end view of the luminaire of FIG. 9.

FIG. 12 is a second end view of the luminaire of FIG. 9.

FIG. 13 is a first side elevation view of the luminaire of FIG. 9.

FIG. 14 is a second side elevation view of the luminaire of FIG. 9.

FIG. 15 is a top plan view of the luminaire of FIG. 9; and, FIG. 16 is a bottom plan view of the luminaire of FIG. 9.

In general, the top plan views form no part of the claimed design. The elements shown in broken lines are included for the purpose of illustrating portions of the luminaire that form no part of the claimed design.

1 Claim, 12 Drawing Sheets
